UNITED STATES PATENT OFFICE.

JAMES F. GREENSTREET, DECEASED, LATE OF KEWANEE, ILLINOIS; BY ELLA PARKE,
ADMINISTRATRIX, OF KEWANEE, ILLINOIS.

RADIATOR ATTACHMENT.

Application filed April 3, 1923. Serial No. 329,730.

To all whom it may concern:

Be it known that I, ELLA PARKE, a citizen of the United States, residing at Kewanee, county of Henry, State of Illinois, administratrix of the estate of JAMES F. GREENSTREET, late a citizen of the United States, and a resident of Kewanee, in the county of Henry and State of Illinois, deceased (as by reference to the duly certified copy of 10 letters of administration, hereto annexed, will more fully appear), do hereby declare that the said JAMES F. GREENSTREET invented a new and useful Improvement in Radiator Attachments, of which the following is 15 a specification.

This invention has reference to radiator attachments, and its object is to provide an attachment for steam or hot water heating radiators, whereby a circulation of warmed 20 fresh air may be caused.

The invention comprises a casing attachable to the basic portion of a radiator, of standard construction, in elevated relation to the floor upon which the radiator is 25 mounted, and the casing is provided with removable portions of drawer-like construction in underriding relation to the casing and arranged to register with fresh air openings in the wall of the room in which the 30 radiator is located. The arrangement is such that the attachment may be applied to the radiator without any change whatever in the latter and fresh air may be conducted into the room in a rising direction through 35 the radiator so as to become effectively warmed and thereby distributed. The attachment is also susceptible of adjustment to cut off the inflow of fresh air, either in whole or in part, whereupon the radiator 40 will act in a manner similar to ordinary radiators without attachments like those provided by the invention.

The radiator attachment has the advantage of being of a particularly sanitary nature, permitting access to various parts for 45 cleansing and dismantling in whole or in part, and for adapting the attachment to larger or smaller radiators or to restrictions or extensions of the fresh air directing 50 feature.

The invention will be best understood from a consideration of the following detailed description taken in connection with the accompanying drawings forming part of

this specification, with the understanding, 55 however, that the invention is not confined to any strict conformity with the showing of the drawings, but may be changed and modified so long as such changes and modifications mark no material departure from the 60 salient features of the invention as expressed in the appended claims.

In the drawings:—

Figure 1 is an elevation of a radiator with the attachment applied, the upper portion of 65 the radiator being broken away.

Figure 2 is a section on the line 2—2 of Figure 1, with the section continued through the wall of a building to show fresh air ducts 70 leading thereinto.

Figure 3 is a plan view of the casing or box structure.

Figure 4 is a section on the line 4—4 of Fig. 3.

Figure 5 is a section similar to Fig. 2 but 75 taken on a line corresponding to the line 5—5 of Fig. 3.

Figure 6 is a perspective view of a portion of the casing as seen toward one inside corner.

Figure 7 is a perspective view of a latch member forming part of the drawer structure.

Figure 8 is a detail view showing the means for actuating the rear damper, the 85 latter being shown in closed position.

Figure 9 is a view similar to Fig. 8, but showing the rear damper in open position.

Figure 10 is a section on the line 10—10 of Fig. 6.

Referring to the drawings, there is shown in Figures 1, 2 and 5 a radiator 1 which may be taken as indicative of an ordinary steam or hot water radiator, provided with the customary legs 2 by means of which the base of the radiator is elevated a short distance above the floor upon which the radiator is supported, such floor being indicated at 3. It is customary to locate radiators for house-heating purposes close to the wall and usually close to the outer wall of the building and such wall is indicated at 4.

The radiator 1 is shown as of the sectional cast type with the sections provided with hubs 5 at the base portions by means of which the sections are connected together by nipples or otherwise. The legs 2 vary in height in different radiators but such dif-

ferences in height do not affect the invention which is equally applicable to radiators which are hung on the wall of the room by hooks or otherwise.

5 The attachment includes a box or casing 6 extended lengthwise of the radiator and including one or more sections composed of front and back plates 7 and 8 respectively, intended to be placed in front of and to the 10 rear of the radiator, and end members 9 to which may be added an intermediate member 10. Each of the members 9 and 10 may be thicker or of heavier gage material than the front and back members 7 and 8 and may be in the form of a casting, while the front and back members may be of sheet metal, these, however, being features of manufacture. Each member 9 and 10 has the bottom edge formed into a series of steps 15 20 11, 12 and 13 with the bottom edges of the steps 11 and 12 formed with undercut guides 14. At a point about midway of the length of each member 9 and 10 there is a cutaway portion 15 so arranged as to receive one of 25 the hubs 5 on a corresponding one of the sections of the radiator 1, so that the end or intermediate member 9 or 10, as the case may be, rests upon and is supported by the hub of the radiator with the steps 11, 12 30 and 13 at respectively lower levels than the top of the hub.

The front and rear plates 7 and 8 are made fast to the end members 9 by means of pairs of lugs 16, formed on the end and 35 intermediate members, and bolts 17 extending between the lugs and traversing the front and rear plates 7 and 8. The intermediate member 10 differs from the end members 9 in that it has pairs of lugs 16 on 40 opposite faces so as to engage abutting front and rear plates 7 and 8.

While the invention may be so constructed that the front and rear plates may extend the full length of the radiator, it is preferred to make the casing or box 6 of a plurality of parts lengthwise of the box, whereby relatively short boxes may be applied to correspondingly short radiators or to include but a portion of the length of the 50 radiator.

For long radiators two or more of the boxes may be employed, in which case the intermediate members 10 are included, this, in some respects, simplifying the structure 55 and permitting a wider application of the invention without necessitating a corresponding increase in patterns.

The members 9 and 10 being of stepped construction, stop at the front at about the 60 level of the hubs of the radiator sections while the rear ends of the members 9 and 10 drop to a considerably greater extent but may stop short of the floor by a suitable distance so that they do not reach the floor 65 even with radiators having the shortest legs.

For manufacturing reasons the front and rear plates 7 and 8 may be practically identical but because of the greater drop of the rear portions of the members 9 and 10, the rear plates 8 have continuations 18 in the 70 form of plates extending to the bottom of the step 13 where each continuation is formed with an inturned ledge 19. Where the plates 8 and 18 join, the upper edge of the plate 18 is formed or provided with a 75 step 19^a into which the lower edge 20 of the plate 8 extends, the lower edge 20 being outset for a short distance, thereby forming a strengthening bead at the bottom of the plate 8. Similarly the lower edge of the 80 front plate 7 has an outstanding bead 21 and the members 9 and 10 are shaped, as shown at 22, to correspond to the bead formation at the bottoms of the plates 7 and 8. Furthermore, the inner faces of the 85 lower portions of the plates 7 and 8 are provided with lugs 23 entering corresponding notches 24 in the end edges of the members 9 and 10. Such construction permits the rigid joinder of the end and intermediate 90 members 9 and 10 and the front and rear plates 7 and 8 with single bolts 17 where engaging. Similarly the plates 18 have lugs 23 and the step portion 13 of each member 9 and 10 has a notch 24 for the 95 same purpose.

In the particular construction shown, the casing or box is composed of two main members divided intermediately and joined by the intermediate member 10 but it will be 100 understood that where shorter structures are desired the intermediate member 10 is omitted and but one front plate 7 and rear plate 8 with the drop continuation 18 are used, this being permitted by the sectional 105 construction of the device.

Each drop continuation 18, where two are used, is provided near its lower edge with an opening 25 elongated to an appropriate extent and provided on the side of the plate 18 remote from the radiator with a tubular extension 26 corresponding in outline to the shape of the opening 25. The tubular extension 26 is telescoped into a similarly shaped duct 27 extending into the room 115 from the wall 4, which latter is pierced by an opening 28 of like shape to the duct, the opening communicating with the atmosphere outside of the wall. The duct, which may be expanded as it extends into the room, is provided exterior to the wall 4 with a border frame 29 in which there is lodged another frame 30 carrying a deflector plate 31 set at an upward inclination so that air may enter the duct, while rain or the like which 120 may also enter the duct is directed toward the outside of the building. The duct is further protected by a screen 32 and an external frame 33 holding the several parts in place against accidental escape. It will 125 130

be understood that the duct structure described with more or less detail is susceptible of change in various ways as may be desired.

5 The lower end of the box or casing 6 is closed by a drawer structure 34 of similar construction to the casing in that it is made sectional so as to be adaptable to long or short radiators or long or short portions 10 of radiators. Moreover, the drawer structure is so arranged that it may be introduced into or withdrawn from the lower portion of the casing in order to permit cleansing of the latter, and when introduced 15 forms a closure for the bottom of the casing, supplying those parts of the bottom of the casing not provided by the casing itself.

The drawer structure comprises end members 35 similar in some respects to the end members 9, and also includes an intermediate or partition member 36 similar in general respects to the intermediate member 10 of the box or casing structure. The 20 drawer structure likewise is provided at the front of the end members 35 and partition 36 with pairs of lugs 37 by means of which a front plate 38 is secured to the end members and partition by bolts 39. The end 25 and intermediate members of the drawer structure have ledges 40 for receiving and carrying metal sheets 41 constituting the bottoms of the drawers, being also supported by the ledges 19 of the plates 18 30 when the drawers are in the inserted position.

The fronts 38 of the drawer structure have inturned flanges or ledges 42 upon which the front edges of the bottoms 41 rest. The 40 top edges of the fronts 38 have outstanding shoulders or step portions 43 similar to the step 19^a and these steps 43 receive the beads 21 of the front plates 7 when the drawers are pushed in to their limit. When 45 so pushed in the bottom plates 41 engage over and are sustained at their inner edges by the ledges 19. The plates 41 are held against the ledges or flanges 40 by a rod 44 traversing the side members 35 and the 50 intermediate member 36 when present, said rod being secured in place by nuts 45 which may be applied to it outside of the members 35. The end members 35 and intermediate partition member 36 are provided near their 55 lower outer corners with sockets 46 to receive pintles 47 of dampers or closures 48 for laterally elongated openings 49 in the front plates 36. The openings 25 in the plates 18 are similarly provided with doors 60 or dampers 50 carried by pintles 51 engaging in sockets 52 in the end members 9 or intermediate member 10, or both as the case may be. The door or damper 50 is made to open toward the interior of the drawer and 65 the door or damper 47 is also made to open

toward the interior of the drawer, the arrangement being such that with the two doors or dampers connected, the front damper may be made to close the passage controlled by it and at the same time cause 70 the rear damper to open, or the front damper may be opened and by its movement close the rear damper.

In order to permit this operation of the rear damper through the medium of the 75 front damper, which is the only one easily accessible, and also to permit the easy removal of the drawer structure for the purpose of cleaning, the front and rear dampers are connected by a link 53 of special construction shown separately in Fig. 7. Lengthwise the link is bent at a slight angle at or near the mid-point and at the point of bending the outer edge of the link is provided with a projection or shoulder 54. 80 At one end on the edge remote from the shoulder, the link is formed with a projection 55 having one edge 56 rounded, the projection being in the form of a tooth. At the same end and beyond the tooth 55, 85 the link is formed into a hook 57 shaped to project through a slot 58 in an inset portion 59 formed in the damper or door 48. On opposite sides of the slot 58 are lugs 60 arranged to embrace the tooth or projection 55 when the hook 57 is projected through the slot 58 and engages over that portion of the damper immediately beneath the slot 58. The length of the slot is sufficient to permit the insertion or removal of 90 the hook by moving the other end of the link downwardly before the device is assembled, but after assembling this is prevented by the floor 41.

At the other end of the link 53 there is 105 formed a tooth or projection 61 similar to but smaller than the tooth 55 and having an outer rounded edge 62 beyond which there is formed an upturned tooth 63 with a rounded bottom edge 64 continued under the tooth 61 and terminating in an abrupt shoulder 65. The tooth 63 is adapted to project through a slot 66 in a boss 67 pressed rearwardly in the door or damper 50. The boss 67 is formed with a ledge 68 in the 110 nature of a stop catch designed to ultimately engage the shoulder 65 in which case the tooth 63 is extended through the slot 66 and engages behind that part of the boss 67 defining the upper end of the slot 66. 115

When the door or damper 48 is swung rearwardly or inwardly to open position, the inset portion 59 engages the lug 60 and moves the link 53 rearwardly. This causes 120 the rounded side of the tooth 61 to engage the inner face of the boss 67 and swing the damper 50 to the closed position shown in Fig. 8. When the damper 48 is again closed, the link 53 is drawn forwardly, the shoulder 125 on the tooth 63 engaging the upper edge of 130

the slot 66 to swing the damper 50 inwardly to open position as shown in Fig. 5. These movements are permitted by the peculiar shape of the link 53 without the necessity of any keepers or other fastening devices for holding the link in position.

It is also to be noted from Fig. 9, that when the link 53 is drawn outwardly, the latter part of the opening movement of the 10 damper is effected by gravity and the inclined bottom edge 64 of the tooth 63 permits the tooth to drop low enough to ride beneath the upper edge of the slot 66. When the damper 48 is closed, therefore, and the 15 damper 50 is open, the entire drawer structure together with the links 53 may be removed as an entirety, permitting free access to the interior of the attachment for cleaning the same, and may be just as readily 20 slid back into operative position, the pointed ends of the tooth entering the slot 66 until the forward curved edge of the tooth 61 engages the damper 50 in a manner to raise the same.

25 The end members 35 and intermediate member 36 of the drawer, when such intermediate member is used, are each provided with stepped portions corresponding to the steps 11 and 12 of the end members 9, and 30 these stepped portions are formed with grooves 69 to receive the tongues 14, whereby the drawer structure may be moved under and sustained by the casing structure with the drawer structure below the radiator, 35 thereby closing the bottom of the box or casing and constituting the closure therefor.

In order to prevent the dampers 48 and 50 from opening beyond a certain extent, a pintle 51 of the door 50 carries a pin 70 40 having in its path a fixed pin 71 engaged by the pin 70 when the door has opened to the desired extent.

The radiator attachment may be applied to or removed from the radiator without any 45 change whatsoever in the radiator and without any fitting. Moreover, the radiator attachment is susceptible of extension or retraction to fit a large or a small radiator or to provide for the inclusion of a greater 50 or smaller number of radiator sections, whereby a portion only of the radiator may be included in the attachment, if such be desirable.

55 The arrangement is such that when the front door or damper is open, fresh air from the exterior of the building is shut off, and when the front door or damper is closed, fresh air is admitted to a point beneath the radiator to rise through the latter and become heated. Where the attachment includes two or more sections, one section may be utilized and the other or others cut off as occasion may demand.

60 The attachment is susceptible of manufacture in a manner requiring but one set of

patterns for the production of the attachment in any length desired, the extension of length being produced by the mere expedient of adding sections or units all of like construction with the exception of the intermediate partition or partitions, the other parts all being the same whether the attachment be made up of a single unit or a multiple of single units.

70 What is claimed is:—

1. An attachment for radiators for directing air to and through the radiator, comprising a casing made of a plurality of longitudinal sections each having a removable lower portion, means for attaching said casing to an installed radiator without change in the structure of the radiator, and said casing having means for admitting air to the casing from different points with said means connected to operate simultaneously 85 in opposite senses.

75 2. An attachment for radiators for directing air to and through the radiator, comprising a casing attachable to an installed radiator and open at the lower end, a removable closure for the lower end, and oppositely movable connected dampers adjacent the bottom of the casing whereby when one damper is open the other is closed, one of said dampers being carried by said 90 closure.

80 3. An attachment for radiators for directing air to and through the radiator, comprising a casing for enclosing the lower end of the radiator and open at the bottom, and a slidable closure for the lower end of the casing, said casing and closure having connected dampers opening oppositely, whereby when one damper is open the other 95 damper is closed.

100 4. An attachment for sectional radiators for directing air to and through the radiator, comprising a casing formed of front and rear plates and end plates connecting the front and rear plates and having recesses to fit over hub portions of the radiator sections, whereby to support the attachment on the radiator, said end plates presenting upper and lower sections about the 105 hub portions.

110 5. An attachment for sectional radiators for directing air to and through the radiator, comprising a casing having a plurality of front and rear plates, and end and intermediate plates connecting the front and rear plates, the end and intermediate plates having recesses for fitting over the hub portions of the radiator to support said casing.

115 6. An attachment for sectional radiators for directing air to and through the radiator, comprising front and rear plates, connecting plates for the front and rear plates each having a recess for fitting over a hub portion of a radiator section, a slidable closure for the bottom of the casing, and con- 120 125 130

- neected dampers in the casing and slidale portion respectively, both dampers opening inwardly and oppositely, whereby when one damper is opened the other closes. 70
- 5 7. An attachment for sectional radiators for directing air to and through the radiator, comprising a casing having front and rear plates, and connecting plates for the front and rear plates each having a recess 75 for engaging the hub portion of a radiator section, and a removable member constituting a closure for the bottom of the casing and coacting with the front and rear portions and the end plates of the casing, said rear portion of the casing dropping to a lower level than the front portion, and damper structures in the rear portion of the casing and the front portion of the removable member and having connections between the damper structures with both damper structures opening inwardly, whereby when one damper structure is opened the other closes. 80
- 10 8. An attachment for sectional radiators for directing air to and through the radiator, comprising a casing formed of a plurality of front plates, a plurality of rear plates and a plurality of end and intermediate plates joining the front and rear plates, the casing being open at the lower end, a closure for the lower end of the casing comprising a plurality of front plates and a plurality of end and intermediate plates, dampers in the rear plates of the casing and the front plates of the closure, and connecting means between the dampers with said dampers opening inwardly, whereby when one damper is opened the other damper closes. 85
- 15 9. An attachment for radiators for directing air to and through the radiator, comprising a casing for the lower end of the radiator and open at the bottom, a closure for the lower end of the casing and removable therefrom, dampers in the lower end of the casing and closure respectively, and connecting means for the dampers movable into and out of engaging relation to the dampers, whereby the closure may be moved into closing relation to the casing or removed therefrom at will and without the aid of tools. 90
- 20 10. An attachment for radiators for directing air to and through the radiator, comprising a casing for the lower end of the radiator and open at the bottom, a closure for the lower end of the casing and readily attachable to and removable from the casing, damper structures in the lower end of the casing and closure respectively, and a connecting member for the damper structures free from direct connection to either and movable into engaging relation to both, said damper structures both opening inwardly, whereby the damper structures 95
- 25 may be simultaneously moved, one into closed position and the other into open position, and the closure may be applied to the casing or removed therefrom without the aid of tools. 100
- 30 11. An attachment for radiators for directing air to and through the radiator, comprising a casing for enclosing the lower part of the radiator and having means for there supporting it, and a closure for the casing, said casing and closure having coacting tongue and groove portions whereby the closure may slide onto and from the casing. 105
- 35 12. An attachment for radiators for directing air to and through the radiator, comprising a casing for enclosing the lower part of the radiator and having means for there supporting it, and a closure for the casing, said casing and closure having coacting tongue and groove portions whereby the closure may slide into and from the casing, and dampers on the casing and closure opening in opposite directions and provided with connections whereby the opening of either damper causes the closing of the damper connected to it. 110
- 40 13. An attachment for radiators for directing air to and through the radiator, comprising a casing for the lower portion of the radiator, dampers for the casing on oppositely located portions thereof, said dampers being pivoted to swing inwardly with respect to the casing and each damper having a passage therethrough, and a connecting link for the dampers having engaging portions at opposite ends for movement through the passages, whereby the link may be engaged with both dampers or disengaged from the dampers from one side of the casing. 115
- 45 14. An attachment for radiators for directing air to and through the radiator, having inwardly opening dampers, on opposite sides, each with a depressed portion and a passage to which the depressed portion leads, and a connecting link for the dampers having latch ends for entering the passages as guided thereinto by the depressed portions. 120
- 50 15. An attachment for radiators for directing air to and through the radiator, having inwardly opening dampers on opposite sides, each with a depressed portion and a passage to which the depressed portion leads, and a connecting link for the dampers having latch ends for entering the passages as guided thereinto by the depressed portions, and each end of the link having a hook at the end and a shoulder back of the hook. 125
- 55 16. An attachment for radiators for directing air to and through the radiator, having inwardly opening dampers on opposite sides, each with a depressed portion and a passage to which the depressed portion 130

leads, and a connecting link for the dampers having latch ends for entering the passages as guided thereinto by the depressed portions, and each end of the link having a hook at the end and a shoulder back of the hook, said link also having its lower edge provided with a projection by which it may be rockably supported.

In testimony that I claim the foregoing

as the invention of JAMES F. GREENSTREET, 10
I have hereto affixed my signature in the
presence of two witnesses.

ELLA PARKE,
